UNITED STATES PATENT OFFICE.

CHARLES H. FORBELL, OF WOODHAVEN, NEW YORK.

DESIGN FOR AN IMAGE.

41,211.

Specification for Design.

Patented Mar. 7, 1911.

Application filed December 16, 1910. Serial No. 597,718. Term of patent 7 years.

To all whom it may concern:

Be it known that I, CHARLES H. FORBELL, a citizen of the United States, residing at Woodhaven, Queens county, city and State of New York, have invented a new, original, and ornamental Design for Images, of which the following is a specification, reference being had to the accompanying drawing, forming part thereof.

front elevation showing the design of the article.

I claim:

The ornamental design for an image as shown.

CHARLES H. FORBELL.

Witnesses:

IRVING M. OBRIEIGHT,
FLORENCE LERIEU.
